CLEANSER DEVICE

Russell B. Kingman, Orange, N. J., assignor to
 Metal Textile Corporation, West Orange, N. J.,
 a corporation of Delaware

Application July 20, 1935, Serial No. 32,347

2 Claims. (Cl. 15—122)

This invention relates, generally, to improvements in cleanser devices; and the invention has reference, more particularly, to a novel hand implement for general washing and cleaning operations, such as shown in my prior Patent No. 2,026,638, dated January 7, 1936, which discloses a foraminous resilient body having portions of its surface area covered with metallic mesh.

The invention has for an object to provide a cleanser device comprising a hollow resilient porous body, such, for example, as provided by sponge rubber, the interior of which is filled with a mass of fibrous material alone or treated with a saponaceous substance, or with any suitable form of saponaceous substance alone or in combination with a carrier therefor, or mixed with other ingredients calculated to contribute to cleansing or other effects by which the device is desired to be functionally characterized; said body also including elements adapted to effect an abrasive or scouring action upon the surfaces to which it is applied when conducting a cleaning operation.

Other objects of this invention, not at this time more particularly enumerated, will be understood from the following detailed description of the same.

Illustrative embodiments of this invention are shown in the accompanying drawing, in which:

Fig. 1 is a face view of one form of the cleanser device according to this invention, showing the same provided with a facing of metallic mesh fabric to serve as a scouring or scraping medium; Fig. 2 is a longitudinal sectional view of the same; and Fig. 3 is a fragmentary longitudinal sectional view of a modified form of this type of cleaner device.

Similar characters of reference are employed in the hereinabove described views, to indicate corresponding parts.

Referring to the drawing, the novel cleanser device according to this invention is shown therein to comprise a suitably shaped hollow body of resilient porous material, such e. g. as sponge rubber. In one form, as shown in Figs. 1 and 2, the hollow body comprises a hollow or chambered upper section 10 providing an interior chamber 11, and a bottom section 12 suitably secured to said upper section 10 in closing relation to said chamber 11. Owing to the interstitial or highly porous character of the hollow body, its walls are pervious to liquids. Enclosed within the hollow body, so as to fill the interior thereof, is a mass of fibrous or filamentary material 13. This filler mass while more or less compacted is, nevertheless, yieldable or resilient, and consequently suit-

ably supports or backs the walls of the hollow body when the same is applied to a surface to be cleaned; and, in fact, the body, due to its own resilient character and that of the filler mass therein, will readily conform itself to the contours of the surface to which it is applied and pressed, and over which it is rubbed, when employed in cleaning such surface. The filler mass 13 may comprise any suitable material; for example, wood shavings, excelsior, vegetable fiber, or a mass of filamentary material of any other specific character may be employed.

It will be obvious that in the use of the device, in the simple form above described, and owing to the pervious character of its body and of the filler mass contained therein, that the same will take up and then emit during cleaning operations therewith, any desired cleansing liquid, such, for example, as soapy water, cleaning oils, or the like.

In a preferred embodiment of the invention, the filler mass comprises woody or other preferably absorbent fibrous material which is impregnated, at the time of manufacture of the device, with a suitable saponaceous material; the filler mass in such case serves as a carrier for the saponaceous substance, and consequently, when the device is wetted preparatory to use, the liquid will enter and contact with the saponaceous substance carried by the filler mass to form a soapy mixture which will be expressed from the device as it is rubbed over a surface desired to be cleansed.

If desired, the bottom section of the device, instead of being made of interstitial or porous material, such as sponge rubber, may comprise a vulcanized mass of rubber filled or impregnated with a pulverant abrasive material, such e. g. as powdered emery, carborundum, pumice stone, or the like, as indicated at 15 in Fig. 3. The bottom section 15 thus provided may be vulcanized directly to the sponge rubber upper section 10 in closing relation to the interior chamber 11 thereof, thereby assuring a secure and irremovable relation of the one to the other.

As also shown in the drawing, a metallic mesh fabric 16 is applied over the top and around the sides of the upper section 10 of the device. This mesh fabric 16 is preferably of a knitted formation, produced from flat ribbon-like wire or strand, although other cross-sectional shapes of the wire or strand may be employed. It is also preferable that the wire or strand employed in the production of the mesh fabric be of a substantially non-corrosive metal, such e. g. as zinc, copper or aluminum. The free marginal portions 17 of the metallic mesh fabric 16 are turned under

the bottom marginal portions of the upper section 10 of the device, whereupon the bottom section 12 is secured over said mesh marginal portions 17 and to the upper section 10. Preferably the bottom section 12 is thus secured by vulcanizing the same in strongly merged or adhered relation to the upper section, thereby not only assuring a secure and irremovable relation of the one to the other, but also assuring a strong holding grip upon the mesh marginal portions 17, so that the mesh fabric 16 will not loosen from its enveloping relation to the exterior surfaces of the upper section 10 of the device when the latter is subjected to the strains of use. In utilizing the thus modified form of cleanser device, the foraminous body sections and its filler mass may be wetted to exude a saponaceous cleaning liquid when rubbed over a surface to be cleaned, while at the same time its mesh faced areas, being resiliently backed by the body of the device, will be firmly pressed against and in conforming relation to said surface, so that, as the device is rubbed back and forth upon the latter, the edges of the metallic loops of the mesh will exert a strong scraping effect, well calculated to loosen and scrape away encrusted and caked dirt and soil; especially is this so when the wire of the mesh is of flat ribbon-like or other angular cross-sectional form, since, in such case, sharp chisel-like edges are presented in various directions which assure a highly efficient scraping action.

It will be understood that further modifica-

tions of the specific details of construction and form, other than those already indicated, may be made, and that various combinations of the functional parts described may be made, without departing from the scope of this invention as defined in the herefollowing claims. Hence, I do not limit myself to the exact arrangements and combinations of the materials and parts described in the foregoing specification, nor do I confine myself to the exact details of the construction of the device and its parts as illustrated in the accompanying drawing.

I claim:

1. A cleaner device comprising a resiliently compressible hollow body adapted to enclose expressible saponaceous material, portions of the body wall being made of sponge rubber through which saponaceous material may be expressed, and a metallic mesh secured to said body in externally overlying relation to the sponge rubber wall portions thereof.

2. A cleaner device comprising a resiliently compressible hollow body adapted to enclose expressible saponaceous material, portions of the wall body being made of sponge rubber through which saponaceous material may be expressed, and an abrasive mesh of knitted ribbon-like metallic wire secured to said body in externally overlying relation to the sponge rubber wall portions thereof.

RUSSELL B. KINGMAN.
